UNITED STATES PATENT OFFICE.

JAMES L. WALKER, OF SUMMERTON, SOUTH CAROLINA.

AUTOMATIC TRAIN-STOP.

1,218,496.

Specification of Letters Patent. Patented Mar. 6, 1917.

Application filed December 4, 1915. Serial No. 65,084.

To all whom it may concern:

Be it known that I, JAMES L. WALKER, a citizen of the United States, residing at Summerville, in the county of Dorchester and State of South Carolina, have invented new and useful Improvements in Automatic Train-Stops, of which the following is a specification:

This invention relates to improvements in 10 automatic train stopping apparatus and has particular application to apparatus of the class described whereby the propelling power of the motor car may be cut off and the brakes applied in the event of the train 15 entering the danger zone.

In carrying out the present invention, it 20 is my purpose to provide automatic train stopping apparatus which will operate efficiently and effectively under all conditions, which may be installed and maintained at small cost, and wherein the component parts will be so arranged and correlated as to reduce the possibility of derangement to a minimum and enable access to be 25 had to the apparatus for the purposes of cleaning and repairing.

With the above and other objects in view, the invention consists in the construction, combination and arrangement of parts hereinafter set forth in and falling within the scope of the claims.

In the accompanying drawings;

Figure 1 is a diagrammatic plan view of 30 train stopping apparatus constructed in accordance with the present invention.

Fig. 2 is a cross sectional view through the trackway showing the obstacle.

Fig. 3 is a horizontal sectional view through the obstacle.

Fig. 4 is an enlarged fragmentary side elevation of the controlling valve and its support.

Fig. 5 is a plan view of the throttle lever showing a modified construction.

Arranged along the trackway are track 50 obstacles preferably disposed adjacent to the respective road signals. In the present instance, each track obstacle comprises a vertical shaft 1 journaled in alining bearings 2 suitably secured to the road bed. Secured to the upper end of the shaft 1 and arranged at right angles thereto is an arm 3, while fastened to the shaft between the bearings 2 is a stop arm 4 adapted to 55 abut one of the bearing supports to limit the movement of the shaft in one direction.

Secured to the lower end of the shaft is a crank arm 5 connected through the medium of a yieldable connection 6 with a rod 7 capable of longitudinal movement and connected through the medium of suitable mechanism 8 with the signal blade of the adjacent semaphore. In the present instance, the connection 6 comprises a sleeve 9 having one end threaded onto the end 65 of the rod 7, a plug 10 threaded into the remaining end of the sleeve and formed with an axial bore 11, and an eye bolt 12 passed through the bore 11 and having the eye thereof secured to the crank arm 5, and 70 the inner end equipped with a nut 13. Interposed between the nut 13 and the plug 10 and surrounding the eye bolt is a coiled expansion spring 14.

Normally, the arm 3 lies parallel with the 75 trackway and when a signal blade of the semaphore moves to danger position motion is transmitted through the mechanism 8, rod 7 and yieldable connection 6 with the crank arm 5 to rotate the shaft 1 and 80 swing the arm 3 to horizontal or tripping position. By means of the yieldable connection 6 between the crank arm and the rod 7, the arm 3 and the shaft 1 may move relatively to the rod so as to prevent mutilation 85 of the arm 3 in the event of a car step or other rigid article striking the arm in the passage of a train.

Bolted or otherwise connected to the pilot beam of the locomotive and projecting rearwardly therefrom is a bracket 15 comprising top and bottom bars 16 and 17 respectively and end bars 18, 18. Suitably fastened to the top bar 16 is a valve 19 of some suitable construction and this valve is connected in the brake pipe 20 of the air brake system of the train and secured to the stem of the valve 19 and projecting outwardly therefrom at right angles thereto is a lever 21, while pivoted to the outer end of the lever 21 is one end of a link 22. The other end of the link 22 projects through an opening 23 formed in the bottom bar 17 and is formed, adjacent to its lower end, with an aperture 24. 25 designates a bolt capable 100 of sliding movement and formed with elongated slots 26 through which are passed securing bolts 27 that hold the locking bolt secured to the under surface of the bottom bar. One end of the bolt 25 is adapted to 110 enter the aperture 24 in the lower end of the link 22, while the remaining end of the

locking bolt is downturned as at 28 and disposed adjacent to the forward end bar 18 of the bracket. The forward end bar of the frame projects below the bottom bar 5 and secured to the depending end of such end bar is a yoke 29 and pivoted within the yoke 29 is a trip lever 30 having one end adapted to engage the downturned end 28 of the locking bolt to slide the latter to release the link, and the remaining end adapted to strike the active trip arm 3 of the obstacle. 31 designates a clip suitably secured to the valve lever 21 at the connection between such lever and the link 22 and 15 secured to this clip is one end of a retractile spring 32, the remaining end of the spring being fastened to the forward end bar of the bracket.

Normally, the valve 19 is closed and the bolt 25 in engagement with the aperture 24 in the link 22 to hold the valve closed against the action of the spring 32. When, however, the lower end of the trip lever 30 strikes an active arm 3, the trip lever 25 is swung and the upper end thereof engages the downturned end 28 of the locking bolt with the effect to slide the locking bolt and release the link and when the link is released of the influence of the locking bolt, 30 the spring 32 reacts and swings the valve lever 21 so as to open the valve 19. Thus, the brake pipe is placed in open communication with the atmosphere to effect an application of the brakes to the wheels.

35 In the present instance, I have shown the throttle valve lever 33 of the locomotive connected with a motor 34 of some suitable construction, and the whistle 35 of the locomotive is connected with a motor 36 of suitable construction. These motors 34 and 36 are preferably of the fluid type and are connected by means of an air pipe 37 with the pipe leading from the triple valve of the brake system to the brake cylinders. 40 Thus, when the pressure in the brake pipe is reduced, incident to the opening of the valve 19, and the triple valve actuated to establish communication between the auxiliary reservoir and the brake cylinders, the 45 air flowing from the auxiliary reservoir will flow through the pipe 37 into the motors 34 and 36 to actuate such motors and close the throttle valve and sound the whistle.

In the present instance, a pressure operated valve 37' is located in the pipe 37 and controls communication between the latter and the motor 36. In the present instance, this valve comprises a cylinder 40 formed of two sections detachably connected to each other, and a piston 41 mounted within the cylinder. Secured to the piston 41 is a piston rod 42 projecting outwardly through one end wall of the cylinder and encircling the piston rod 42 and threaded 65 into the end wall of the cylinder through

which the piston rod projects is an adjusting nut 43, while surrounding the piston rod between the adjusting nut and the piston is a coiled expansion spring 44 acting to hold the piston in normal position and to restore the same to such position. Threaded on the outer end of the piston rod is a nut 45 acting to limit the movement of the piston under the action of the spring. The cylinder 40 is formed with a port above the normal position of the piston and a port below the normal position of the piston and these ports are connected with the pipe 37, as clearly illustrated in Fig. 1 of the drawings. The spring 44 acts to hold the piston 41 in normal position upon a service application of the brakes, while upon an emergency application, the increased pressure in the pipe 37 slides the piston 41 against the action of the spring to establish communication between the ports in the cylinder, thereby permitting the air in the pipe 37 to flow into the motor 36.

In the modified construction illustrated in Fig. 5, I have shown the chain connected with the motor 34 as connected to a relatively long throttle lever and when the motor 34 is associated with such lever, a bell crank lever 46 is pivoted upon the long throttle lever at a point between the ends of such lever and one leg of the bell crank lever is connected to the chain, while the other leg is connected to the dog rod.

If desired, a spring 47 may be employed to hold the trip lever 30 against the movement due to the vibration of the engine, as illustrated in Fig. 4.

While I have herein shown and described one preferred form of my invention by way of illustration, I wish it to be understood that I do not limit or confine myself to the precise details of construction herein described and delineated, as modification and variation may be made within the scope of the claims and without departing from the spirit of the invention.

I claim:

1. In train stopping apparatus, the combination with the brake pipe, of a valve located in the brake pipe, a lever connected to the stem of said valve, a bracket disposed in juxtaposition to said valve, a bolt slidably mounted upon said bracket, a link having one end pivoted to said lever and the remaining end formed with an aperture to receive said bolt whereby the valve will be held in closed position, and means connected to said lever to swing the valve to open position upon the withdrawal of the bolt from the aperture in said link.

2. In train stopping apparatus, the combination with the brake pipe, of a valve located in the brake pipe, a lever connected to the stem of said valve, a bracket disposed in juxtaposition to said valve, a bolt slid-

ably mounted upon said bracket, a link having one end pivoted to said lever and the remaining end formed with an aperture to receive said bolt whereby the valve will be held in closed position, and a spring connected to said lever to actuate the latter to open the valve upon the withdrawal of the bolt from the aperture in said link.

3. In train stopping apparatus, the combination with the brake pipe, of a valve located in the brake pipe, a lever connected to the stem of said valve, a bracket disposed in juxtaposition to said valve, a bolt slidably mounted upon said bracket, a link having one end pivoted to said lever and the remaining end

formed with an aperture to receive said bolt whereby the valve will be held in closed position, means connected to said lever to swing the valve to open position upon the withdrawal of the bolt from the aperture in said link, and a trip lever pivoted upon said bracket and adapted to slide said bolt to release said link. 20

In testimony whereof I affix my signature in presence of two witnesses.

JAMES L. WALKER.
